UNITED STATES PATENT OFFICE

2,688,407

ROTARY TABLE CONVEYER FOR
CLEANSING APPARATUSErich R. Zademach, Hillside, N. J., assignor to
Metalwash Machinery Company, Irvington,
N. J., a copartnershipOriginal application October 15, 1940, Serial No.
361,211, now Patent No. 2,443,091, dated June
8, 1948. Divided and this application June 4,
1948, Serial No. 31,108

1 Claim. (Cl. 211—41)

This invention relates to apparatus for the continuous fluid treatment of articles traveling on an enclosed conveyor, and is particularly directed to apparatus for continuously subjecting articles to washing and drying operations or other successive steps employing any desired combination of liquid or gas treatments. It has been particularly developed for use in washing and drying pans and other containers generally employed in commercial bakeries. In this field the pans are first subjected to washing with jets of hot water carrying suitable detergents, followed by drying with jets of heated air.

The present application constitutes a division of my copending application Serial No. 361,211 filed October 15, 1940, now Patent No. 2,443,091, issued June 8, 1948.

The cleaning of baking pans and the like introduces special problems in apparatus of this type, due partly to the shapes and sizes of such pans and utensils, and partly to the type of cleansing and drying action to which they must be subjected. Certain features of the invention are particularly intended to facilitate the treatment of articles of this type. In particular, special supporting means has been provided for holding such articles in proper position in minimum space.

Other objects and advantages will appear from the detailed description of the preferred embodiment illustrated in the accompanying drawings in which

Fig. 1 is a top plan view of the apparatus;

Fig. 2 is a fragmentary vertical section taken on line 2—2 of Fig. 3;

Fig. 3 is a fragmentary top plan view of Fig. 2; and

Fig. 4 is a fragmentary vertical sectional view on line 4—4 of Fig. 2.

The invention is illustrated by an apparatus particularly adapted for use in cleaning various types of pans used in commercial baking. It comprises in general a substantially annular treating chamber 10 which is divided into a washing zone, a rinsing zone, a drying zone and a feed discharge zone. The treating chamber 10 is formed by suitable sheet metal walls including a bottom, cylindrical inner wall 12, outer wall 13 and top 14 to form a complete enclosure except at the feed and discharge opening 44 through the outer wall 13.

A suitable annular conveyor 17 is supported and rotated in chamber 10. The conveyor includes an article supporting grate 17' having an outer rim 19 and cylindrical grate support 20, which is in the form of a sheet metal cylinder 21.

2

The grate support cylinder 21 extends upwardly substantially to the top of the available space for the articles to be washed and carries along its inner face, preferably adjacent the upper end, an annular rail 24 resting on a series of rollers 25 rotating in bearings 26 mounted on an inner wall 12 of the treating chamber. Rail 24 advantageously extends between flanges 27 on rollers 25 to maintain the grate 17 in radial alignment.

10 A suitable arrangement is provided for revolving the grate 17 at the desired speed. For this purpose the rail 24 is provided with an inwardly extending annular rack 80 engaged by pinion 81 extending through a restricted opening in the inner wall 12 and driven through vertical shaft 82a.

15 The grate sections 17' are removably mounted on rods 105, each section being provided with hook-shaped hangers 113 of sheet metal fitting over rods 105 and advantageously extending around the rods to a sufficient distance to prevent substantial radial movement of sections 17'.

20 In the construction illustrated the grate sections 17' are provided with utensil supports appropriately spaced to carry ordinary utensils in the usual manner, but are provided in addition with generally radial openings into which the lower margin of a flat utensil may be inserted appropriately so as to support it in upright position during treatment. In the form illustrated each section 17' is provided with a plurality of pairs of parallel grate bars 134 mounted at their ends on inner frame bar 114 and outer frame bar 115. Between contiguous pairs of bars 134 an intermediate pair of parallel grate bars 135 is located, attached at their outer ends to outer frame bar 115 and having their inner ends 136 deflected laterally and attached to adjacent bars 134. An intermediate bar 135 is also located parallel to and adjacent each side bar 112 and is similarly mounted at its ends to bar 115 and adjacent bar 134. Filler bars 137, connected at their outer ends to frame bar 115, are located in the outer parts of the tapered spaces between each bar 135 and the bar 134 to which it is connected.

25 Suitable means is provided for supporting a flat utensil inserted between parallel bars of a grate section 133 far enough to support such utensil in generally upright position by engagement with such parallel bars. For this purpose supporting members connected to the grate bars, and which may serve likewise to hold such bars in position, are utilized. In the illustrated construction outer cross rod 137a extends parallel to outer frame bar 115, passing through and engaging

bars 134, 135 and 137, and is fixed at its ends to side bars 112. Inner cross rod 139 is located a short distance from and generally parallel to inner frame bar 114, and likewise extends through and engages bars 134, 135 and 137, with its ends mounted on bars 112. With this arrangement a corner of a flat utensil may be inserted between adjacent bars 134 or 135 with its bottom edge resting on rod 137a and its inner edge bearing against rod 139. Bars 134 will be spaced appropriately to permit utensil 130 to tilt slightly, holding it in place by engagement of its opposite faces with bars 134 or 135. By suitably positioning rods 137 and 139, utensils may be effectively supported in this manner.

It is frequently desirable to provide additional support to limit downward projection of the utensils, to serve as a guide in rapidly locating the utensils in proper position, or for both purposes. This is accomplished in the form shown by providing a support rod 140 located below the grate section 17' between rods 137a and 139, and appropriately attached to the section, arranged to engage the lower margin of a utensil 130 and to retain it in proper position. In the arrangement 25 illustrated rod 140 extends along the lower margins of bars 112, 134, 135 and 137 and is suitably attached thereto as by welding. Filler bars 137 project to or slightly beyond rod 140, which provides appropriate support for the inner ends of such bars, and is suitably attached thereto as by welding. Suitable short brace rods 141 may be fixed at their ends to adjacent bars 134 and 135 intermediate rods 140 and 139 to provide additional rigidity.

An arrangement for mounting and supporting the frame rods 105 is also disclosed in Figs. 2 and 3. In this construction an annular mounting angle 142 is fixed to the lower margin of the cylindrical grate support 20 as by welding, and the conveyor frame rod mounting plates 106 are detachably connected to angle 142 as by bolts 143. The outer ends of frame rods 105 are detachably connected to the outer frame rim 19 as by screws 144 extending through the rim and threaded into the ends of rods 105. This construction is relatively simple and inexpensive, and permits ready assembly and disassembly, repair and replacement of damaged parts without requiring any general dismantling of the 50 machine.

I have described what I believe to be the best embodiments of my invention. I do not wish, however, to be confined to the embodiments shown, but what I desire to cover by Letters Patent is set forth in the appended claim.

What is claimed is:

In an annular substantially horizontal rotary table conveyor for advancing articles to be treated along an annular treating apparatus, a first rail arranged along the inner circumference of the conveyor; a second rail arranged along the outer circumference of the conveyor; first and second pairs of parallel bars interconnecting said rails; a third pair of parallel bars, between said first and second pairs of bars, attached at their outer ends to said second rail, and having their inner ends deflected laterally and attached to ones of said first and second pairs of parallel bars; and three radially spaced support elements 10 interconnecting the member bars of each pair of bars; said elements serving to subjcantly support rectangular trays in upright position on two of their adjoining edges.
